UNITED STATES PATENT OFFICE.

FRANK J. KARG AND LEO HERMAN, OF TALLMADGE, OHIO, ASSIGNEES TO THE HERMAN MACHINE AND TOOL COMPANY, OF AKRON, OHIO, A CORPORATION OF OHIO.

PULLEY.

Application filed January 28, 1924. Serial No. 689,122.

To all whom it may concern:

Be it known that we, FRANK J. KARG and LEO HERMAN, citizens of the United States and residents of Tallmadge, county 5 of Summit, State of Ohio, have invented certain new and useful Improvements in Pulleys, of which the following is a specification.

This invention relates to pulleys and has 10 as its object the securing of certain advantages and improvements over pulleys at present in use. One of the purposes of the invention is to provide a pulley having greater frictional properties than pulleys 15 heretofore constructed, and to provide a pulley the surface of which is yielding so that it cannot be easily dented or injured. The invention also provides a pulley the 20 surface of which, when heated, will have increased friction properties. The pulley is also waterproof, which is a decided improvement over the ordinary or well known paper pulley.

The objects which have been stated are 25 obtained by the pulley construction herein shown and described, and other objects may be apparent to those skilled in the art. In carrying out the invention, however, it is not necessary that the details herein shown 30 and described be followed as changes and modifications may be made within the scope of the appended claim.

In the drawings:

Figure 1 is a side view of a pulley constructed in accordance with the invention;

Figure 2 is a longitudinal section on the line 2-2 of Figure 1;

Figure 3 is a section on the line 3-3 of Figure 2, layers of the fabric being broken 40 away to show certain details of the construction;

Figure 4 is a view looking at one end; and

Figure 5 is a view looking at the opposite end.

The pulley shown herein is one such as used on motor shafts, but it is apparent that the invention is of general application. In the form shown there is provided the usual central sleeve 1 which fits over the shaft and is provided with a keyway 2 over 50 which is positioned the usual set screw 3. The ends of the sleeve are provided with teeth 4 within which fit the end plates 5, long posts or pins 6 being passed through

the end plates and through the body of 55 the pulley and riveted over at their extremities to secure the plates together. One end of the sleeve is cored out as at 7.

In the present pulley construction, the body is composed of a plurality of layers of 60 rubberized fabric which have, preferably, been vulcanized. A convenient and economical source of supply for the fabric is found in old tire casings, either of the cord or fabric type, although the invention is 65 not necessarily limited to the use of this material as fresh fabric may be used. The layers of rubberized fabric are indicated by the numeral 10, cross woven fabric or canvas being indicated in Figure 3, although, as 70 has been stated, other fabrics may be utilized for this purpose.

In the manufacture of the pulley, pieces 75 of fabric slightly larger than the size required are cut from the sheets of material, with their centers removed and with openings for the pins 6. The required number of pieces are assembled about the central shaft and the pins and between the two end plates. Pressure is then applied to firmly 80 compact the layers together with their faces in substantial contact and while so compacted the pins are riveted in position so that the pulley presents a substantially firm outer surface. The pulley is then turned to 85 the desired profile and a hole 11 bored out for the admission of the set screw. In assembling the layers of fabric, the pieces will be so arranged that the threads thereof are at angles to one another indiscriminately, 90 and are therefore presented at a great variety of angles to the surface of the pulley.

The pulley shown herein possesses many 95 advantages over existing forms of pulleys as will be enumerated. The ends of all of the threads are presented to the surface of the pulley which greatly increases its frictional properties and its wear resisting qualities, both of which features are enhanced by the fact that these threads are at 100 all angles to the surface due to the indiscriminate angular position of the fabric layers. The rubberized fabric is waterproof and will not break down or disintegrate if 105 wet, which is a considerable advantage over paper pulleys in use at the present time. The pulley is inexpensive to manufacture, and while its surface is slightly yielding or re-

slient, it is firm, due to its having been assembled under pressure. The yielding surface gives a better belt contact and, in addition, cannot be easily marred or dented. In addition to this feature, when the pulley is heated during operation, the rubber will soften slightly and ooze out between the plies of fabric, still further increasing its driving capacity.

10 Other objects and advantages will be apparent from the description of the invention and it will be understood that changes and modifications may be made within the scope of the invention as defined hereunder.

What is claimed is:

A pulley embodying a central sleeve and end plates, the body of the pulley being composed of a plurality of separate layers of previously vulcanized, thoroughly impregnated, rubberized fabric, the layers being arranged in a variety of angular relations to one another so that threads of the fabric are presented endwise of the pulley and the layers being held together by pressure between the end plates.

FRANK J. KARG.
LEO HERMAN.
